The ornamental design for a venetian blind slat, as shown.

DESCRIPTION

FIG. 1 is a front perspective view of the venetian blind slat of FIG. 1;

FIG. 2 is a top view in elevation of the venetian blind slat of FIG. 1;

FIG. 3 is a front view in elevation of the venetian blind slat of FIG. 1;

FIG. 4 is a bottom view in elevation of the venetian blind slat of FIG. 1; and,

FIG. 5 is an end view in elevation of the venetian blind slat of FIG. 1 as seen from the left-hand side of FIG. 1, the right end view being a mirror image of FIG. 5.

FIGS. 2-4 have been shown broken away for ease of illustration.

FIG. 1

FIG. 2

FIG. 3

FIG. 4

FIG. 5
